UNITED STATES PATENT OFFICE

VINCENT J. BURNELLI, OF NEW YORK, N. Y., ASSIGNEE TO THE UPPERCU-BURNELLI CORPORATION, A CORPORATION OF DELAWARE

AIRPLANE CONSTRUCTION

Application filed February 4, 1932. Serial No. 337,188.

This invention relates to the frame construction of airplane fuselages, and my improvement is directed particularly to the simple and economical manufacture and assembly of the elements comprised in a metallic frame structure wherein the use of gussets is avoided and angle longérons are employed of sufficient width to provide the required area for riveting thereto the bulkheads and diagonal members.

Another feature of my invention consists of the fuselage construction adapted to provide the requisite strength therein in view of its unusually large size, and the novel character of the trussing employed to suit certain structural conditions, all as will be explained in detail in the accompanying description.

Other features and advantages of my invention will hereinafter appear.

In the drawings:—

Figure 1 is a side elevation of an airplane fuselage, without the covering.

Fig. 2 is an enlarged detail, in perspective, showing a portion of a longéron, and a bulkhead and diagonal members attached thereto.

Fig. 3 is a plan view of Fig. 1.

Fig. 4 is a detail view of a bulkhead on line 4—4 of Fig. 3.

Fig. 5 is a detail view of the front spar bulkhead, and

Fig. 6 is a detail view of the rear spar bulkhead.

In said figures let 1 indicate the upper longérons, and 2 the lower longérons of an airfoil fuselage, the airplane indicated being of the Burnelli type.

These longérons, see the detail view, Fig. 2, are metallic angle bars, having the wide flanges 3, 4, the extended width thereof serving to provide sufficient riveting area for the attachment thereto of bulkheads and diagonals, which heretofore required the interposition of gussets in the joint regions. Thus the bulkhead element 5, of T-shape in cross-section, is shown as having its flanges riveted respectively to the longeron flanges 3, 4, the width of the latter affording ample area for the application of a sufficient number of

rivets to assure the creation of a secure union between the connected elements.

For bulkhead reinforcement, a plate 6 is placed across the angle of the angular members of the bulkhead element, said plate being riveted to the web of said element.

Also the diagonal elements 7, of T-shape in cross-section, are secured by riveting their flanges to the wide flanges 3, 4 of the longeron, without the intervention of gussets.

In Fig. 3 I have shown a fuselage structure of unusual size. This view is a top plan, showing the upper longérons 1 at each side of the fuselage, and also an intermediate lengthwise stiffening member 8 (see Fig. 4) co-extensive therewith, a similar intermediate stiffening member 8a extending intermediate the lower longérons, 2, 2 lengthwise at the fuselage bottom.

These stiffening members 8, 8a are rendered necessary by reason of the relatively large area encompassed in the fuselage which requires that the longérons be supplemented with intermediate reinforcement, both for lengthwise compression purposes and as affording additional anchorages and supports for a double system of trussing which I have found desirable to employ in the production of so large a fuselage.

Between the front-spar bulkhead 9 and rear-spar bulkhead 10, where the greatest strength is required, crossed truss members 11, 11a are provided at each side of the member 8, respectively tying said member to the longérons 1 at opposite sides of the fuselage. Similar crossed truss members (not shown) are provided between bulkheads 9, 10 at each side of member 8a, respectively tying said member to the longérons 2 at opposite sides of the fuselage.

Rearward of the rear spar bulkhead 10 are the succeeding bulkheads 13, 14, 15 and 16, trussing 17, 18, similar to that provided between bulkheads 9, 10 being disposed respectively between bulkheads 10 and 14 and between bulkheads 14 and 16, excepting that elements of trussing 17 are angled respectively from the opposite sides of bulkhead 13 to the centres of bulkheads 10, 14; and the elements of trussing 18 are angled respective-

ly from the opposite sides of bulkhead 15 to the centres of bulkheads 14, 16.

Also, truss elements 19 extend respectively from the centre of bulkhead 16 to the opposite sides of the frame 20 which constitutes the fuselage end.

While bulkheads 13, 14, 15 and 16 are substantially alike in their fabricated structure, and are typified in the example of bulkhead 13, shown in Fig. 4, bulkheads 9 and 10, differ therefrom and will now be described.

Bulkhead 9, which is the front-spar bulkhead, includes the horizontal frame elements 21, 21a, respectively toward the upper and lower ends of the bulkhead, and the vertical frame elements 22, 23, 24, 25, 26, in spaced relation across the width of the bulkhead. This bulkhead 9 separates the pilots' compartment or cockpit 27 from the passenger or load compartment 28; and windows 29, 29, located respectively in the partition spaces formed between the vertical elements 22, 23; 22, 24, above horizontal element 21, enable the pilots to view the interior of the passengers' compartments and to see for themselves that the doors are closed and all is in readiness for taking off.

Also between the elements 23, 25 and 24, 26, respectively, doorways 30, 30 are provided as means of communication between the compartments.

The end panels 31, 31 of the frame are reinforced by inclined braces 32, 32 respectively.

Bulkhead 10, which includes the vertical frame element 10a, is provided interiorly with a web 33 that has a central, depending extension 33a which connects with a rectangular structure 34, providing couches at opposite sides of said extension. The web 33 and its extension 33a, which are reinforced by flanges 33b, form boundaries for clearances 35, 36 that render the passenger compartment continuous through said bulkhead.

The contour of the web 33 is such as to provide head room while adding great strength to the bulkhead.

Between the bulkheads 9 and 10 (also between bulkheads 10 and 13) a system of trussing is provided at the respective sides of the fuselage that strengthens the frame while enabling ample window space to be provided for observation purposes, for the use of passengers seated along the walls of the fuselage.

Thus, for example, longitudinal compression members 37 extend between bulkheads 9 and 10 toward their upper portions. These members 37 are intersected centrally by vertical members 38. Inclined trusses 39 extend from the bottom of members 38 to the respective ends of members 37, and inclined trusses 40 extend from the top of members 38 to the respective ends of members 37. The window frames 41 are mounted between the

members 37, 38 and 39, to thereby provide window spaces whose area is relatively unobstructed by trussing.

It will be noted that the lower frame members of bulkhead 9 have clearances 42 provided in their under surfaces, these clearances being intended to afford recesses for the reception of the wheels 43 of a retractable chassis 44 when said wheels have been swung up against the bottom of the fuselage into 75 horizontal positions.

This application is a continuation in part of my application Serial No. 435,481, filed January 6, 1921.

Variations within the spirit and scope of 80 my invention are equally comprehended by the foregoing disclosure.

I claim:—

1. The combination in an airplane fuselage of unusual width having a frame including upper and lower longerons, of upper and lower longitudinal stiffening members located intermediate the longérons and trussing disposed respectively between the longérons and stiffening members. 90

2. The combination in an airplane fuselage of a front spar bulkhead provided with spaced horizontal members and spaced vertical members, window openings being provided between adjacent vertical members, above the upper horizontal member, and doorways being provided between adjacent vertical members and said horizontal members at opposite sides of said bulkhead. 95

3. The combination in an airplane fuselage 100 of a rear spar bulkhead having a frame and a central vertical member, a web extended inwardly from said frame and opposingly from said central member, said web having reinforce flanges at its edge and being contoured 105 to provide suitable clearances.

4. The combination in an airplane fuselage having a number of bulkheads, in spaced relation, of longitudinal compression members between adjacent bulkheads, toward the upper portion thereof, vertical members intermediate said adjacent bulkheads, diagonal truss members extending from the bottom of said vertical members to the respective outer ends of said compression members, and window frames enclosed respectively between said vertical members, diagonal truss members and compression members. 115

5. The combination in an airplane fuselage, having a foldable chassis carrying wheels, of a front spar bulkhead whose frame portion at its bottom is provided with recesses adapted for the reception of said wheels. 120
